DANIEL H. YOUNG AND WILLIAM L. CASS, OF MANCHESTER, IOWA, ASSIGNEES OF ONE-THIRD TO GRANT BRAYTON, OF MANCHESTER, IOWA.

HUMIDIFYING DEVICE FOR OVENS.

1,299,649.

Specification of Letters Patent.

Patented Apr. 8, 1919.

Application filed June 13, 1918. Serial No. 239,780.

To all whom it may concern:

Be it known that we, DANIEL H. YOUNG and WILLIAM L. CASS, citizens of the United States, residing at Manchester, in the county of Delaware and State of Iowa, have invented certain new and useful Improvements in Humidifying Devices for Ovens, of which the following is a specification.

Our invention relates to improvements in 10 humidifying devices for ovens, particularly for bakers' ovens, and the object of our improvement is to supply for bakers' use and for employment by anyone else where the application is in any way desired, means for 15 quickly humidifying an inclosed space before and during the process of heating said space by other means, said humidifying means being regulatable at will.

This object we have accomplished by the 20 means which are hereinafter described and claimed, and which are illustrated in the accompanying drawings, in which Figure 1 is a horizontal section of a part of an inclosure, such as an oven or the like, with our 25 improved humidifying apparatus installed therein; Fig. 2 is an enlarged detail view, giving a longitudinal vertical section of the vaporizing chamber of said apparatus, with parts broken away; Fig. 3 is an enlarged 30 perspective view of portions of the parallel band electrodes and their supports, and Fig. 4 is an end elevation of the regulatable liquid supplying-means for said apparatus.

In said drawings, similar numerals of reference denote corresponding parts throughout the several views.

In Fig. 1 the numeral 28 denotes part of the structure of a baker's oven or any inclosure whose interior is to be humidified. 40 A pipe 27 is carried across the interior of said oven and has one extremity passed through one wall of the oven, the projecting end of the pipe being exteriorly threaded to receive a washer 25 and nut 26 to secure 45 that end of the pipe to the oven-wall, the end of the pipe also being interiorly threaded to receive an exteriorly threaded plug 9. The other end of said pipe is car-

ried through an opening in the opposite wall of the oven, is similarly exteriorly threaded to receive a washer 24 and a nut 23 to clamp it to the oven-wall. A T-coupling 1 is connected to this end of the pipe by its limb 6, the opposite limb 7 being closed by means of a threaded plug 2. Instead of a T-coupling as shown, a chamber of any other desired form may be removably connected to and placed in communication with this end of the pipe 27. The vertically-directed limb 3 of said T-coupling is closed 50 by a removable plug 4 made of some insulating material, and centrally vertically oriented to permit the passage of an insulating tube 14, through which are passed in separated relation the pair of conductors 15 and 16, extending from some source of electrical current not shown. The extremities of said conductors within the T-coupling are connected to the ends of flat conducting bars or strips 18 and 17 respectively, said strips 55 being carried throughout the length of the pipe 27 to terminate near the rear end of the latter.

To properly space the conducting strips 17 and 18 from each other by insulation and insulate them from said pipe, we provide the following spacing and supporting-means. The numeral 19 denotes a cylindrical body of insulating material such as porcelain, which has diminished and exteriorly-threaded oppositely-directed extensions 21. Each 60 conducting strip 17 and 18 is circularly oriented at 22, with the orifices alined in the two strips, the cylinder 19 being positioned between the strips, with the extensions 21 65 passed through said alined orifices 22, and the nuts 20 are placed on the extensions to hold the strips tightly to the shoulders of said cylinder 19. This spaces the strips 70 equally apart from each other and at equal 75 distances from the interior wall of said pipe, the strips being provided with as many of said supports as may be necessary to properly hold up the strips in constant parallel 80 relation.

Referring now to said Figs. 1 and 4, in

which the means are shown for furnishing a regulatable water-supply to the pipe 27, the numeral 12 denotes an inverted-tank delivering from its depending neck water, regulated by air-pressure in a well-known way, to the receiver 13. A small conduit 10 leads from said receiver 13 to said T-coupling 1, and contains a valve-chamber 11 whose valve is regulatable by a hand-wheel to 10 adjustably cut-off the water supply from the T-coupling and pipe. The apparatus shown is designed to maintain a water-level in the pipe 27 a little above the submerged strips 17 and 18 and a little below the longitudinally alined row of orifices 8 in said pipe, the orifices preferably positioned somewhat below the upper wall of the pipe to deliver 15 vaporous steam obliquely into the oven 28. In the operation of the apparatus, the 20 water is first turned into the pipe 27 to fill it to the proper level, and then an electric current at the proper voltage is passed through the conductors and the conducting strips, and since the strips are narrowly 25 spaced and submerged, the current is passed through the intervening water, which quickly heats it to the boiling-point and almost instantaneously converts it into vapor or steam, discharging same into the oven 30 through the row of small orifices 8. It will be seen that this effect is obtained regardless of the heating of the oven by other means, and works practically at once, so that when the oven is closed its contained air is 35 humidified from the beginning to a proper amount, thus correspondingly favoring the proper baking of the bread or other goods in the oven. The valve in said valve-chamber 11 can be used to shut off the water-supply 40 when desired.

The T-coupling 1, or other shaped chamber connected removably to an end of the pipe 27, has its large openings in the limbs 3 and 7 provided for convenience in the introduction of a person's hands to connect or disconnect the electric connections therein, and the removable closures 2 and 4 therefore facilitate this.

The apparatus shown may be modified in 50 various particulars without departing from the invention, and may be used to humidify other inclosures than ovens.

Having described our invention, what we claim as new, and desire to secure by Letters Patent, is:

1. In a device of the character described, an elongated longitudinally-orificed chamber, closed at both ends, and bar-electrodes passed through the length of the chamber, 60 spaced and insulated from each other and from the chamber.

2. In a device of the character described, an elongated longitudinally-orificed chamber closed at opposite ends, bar-electrodes

positioned within said chamber in spaced 65 parallel relation, and insulated from each other and from said chamber.

3. In a device of the character described, an elongated horizontal longitudinally-orificed chamber having open ends with closures therefor, a pair of flat bar electrodes passed through the length of said chamber, and insulating- and spacing-means within the chamber, the electrodes having openings to detachably receive parts of said means 75 whereby the electrodes are mounted in the chamber in equal spaced relation to each other and to said chamber.

4. In a device of the character described, an elongated horizontal longitudinally-orificed chamber in communication with a source of liquid-supply, a pair of flat bar electrodes passed through the length of the chamber in spaced insulated parallel relation, and means for regulating the height of 80 the liquid in said chamber, relative both to the said electrodes and the said orifices in the chamber.

5. In a device of the character described, an elongated horizontal longitudinally-orificed chamber with open opposite ends, detachable closures for said open ends, and a pair of spaced parallel flat bar electrodes carried through said chamber and conductors connected thereto passed through orifices in the chamber and placed in communication with a source of electrical current. 90

6. In a device of the character described, an elongated horizontal chamber having a row of small orifices in its upper wall, one 100 end of the chamber being closed, the other open, a second chamber removably connected to and in communication with the open end of the first-mentioned chamber and provided with hand-holes, removable closures for said 105 hand-holes, and flat-bar electrodes positioned along the length of said chamber interiorly and in communication with a source of electrical current, means for spacing and insulating said electrodes from each other 110 equally and from said chamber, a regulatable source of liquid-supply in communication with said second-mentioned chamber, conductors in communication with said source of electrical supply and passed through and 115 insulated from one of said hand-hole closures and connected respectively to adjacent ends of said electrodes.

7. In a device of the character described, an elongated orificed chamber, a pair of 120 electrodes in said chamber having communication with conductors leading through the wall of the chamber to a source of electric current, and means within said chamber located in a plurality of units along the 125 length of said electrodes to support them in spaced and insulated relation to each other and to the chamber walls, comprising for

each unit a body with oppositely-directed diminished extensions, forming shoulders therewith, the electrodes having vertically aligned openings through which the diminished extensions are passed removably to permit the electrodes to engage said shoulders, said body and its extensions being composed of insulating material, and means for fastening detachably said electrodes upon

said extensions in contact with said shoulders.

In testimony whereof we affix our signatures in presence of two witnesses.
